Atty's.

UNITED STATES PATENT OFFICE.

WAYNE E. DUNSTON, OF KALAMAZOO, MICHIGAN, ASSIGNOR TO THE C. G. SPRING & BUMPER COMPANY, OF DETROIT, MICHIGAN, A CORPORATION OF DELAWARE.

BUMPER.

Application filed November 23, 1922. Serial No. 602,688.

To all whom it may concern:

Be it known that I, WAYNE E. DUNSTON, a citizen of the United States, residing at Kalamazoo, in the county of Kalamazoo and State of Michigan, have invented a certain new and useful Improvement in Bumpers, of which the following is a full, clear, and exact description, reference being had to the accompanying drawings.

This invention relates to bumpers, and more particularly to the means for connecting together the central portions of bumpers comprising a plurality of vertically spaced front or impact bars or plates and an intermediate auxiliary or rear bar or plate. The general object of the invention is to provide a device for connecting the said bars or plates which is particularly efficient in operation; which will provide a non-rattling connection between the parts; and one which will permit the use of symmetrical and interchangeable members. To accomplish the foregoing general objects, as well as others which will appear hereinafter, in and through the construction and arrangement of parts shown in the drawings forming a part hereof, wherein Fig. 1 represents a plan view of a bumper of the type referred to herein, having my invention applied thereto; Fig. 2 a front elevation of the aforesaid bumper; Fig. 3 an enlarged central sectional detail through the bumper and clamping means shown in the preceding views; Fig. 4 a detail in plan view of the parts shown in Fig. 3; and Fig. 5 a detail in elevation of the front or outer member of the clamping device.

Describing the various parts by reference characters, 1 denotes the vertically spaced main plates or bars of a bumper, the said bars extending the full width of the bumper and each being curved rearwardly at its ends, as indicated at 1^a. 3 denotes the rear or auxiliary bar, the bar 3 being preferably straight throughout its length and being shown as connected at its ends to the ends of the front or main bars by means of caps 4, to which the ends of the bars or plates are secured in any desired manner, the details of such connection forming no part of the invention sought to be protected herein. The bumper as a whole is shown as supported from the arms or members 5 by means of clamps 6, which are adjustably mounted upon the rear or auxiliary bar 3 and pivot-

ally connected to the front ends of the arms 5, as indicated at 7. For the purpose of connecting the central portion of the rear or auxiliary bar to the central portions of the front or main bars, I provide a clamp consisting generally of a front or outer seating member 8, and a pair of inner or rearwardly extending clamping members, each indicated generally at 9.

The member 8 is in the general form of a shallow channel having the web 8^a thereof presented rearwardly or toward the vehicle, the flanges 8^b being preferably flared outwardly and provided each with a lateral extension or projection 8^c, the rear or inner face of each such projection being adapted to bear against the front or outwardly presented face of a main bar 1. When assembled, the lower edge of the upper main bar will engage the upper flange 8^b, while the upper edge of the lower main bar will engage the lower flange 8^b, the front or outer faces of the bars engaging the adjacent surfaces of the projections 8^c.

In addition to the projections 8^c, the member 8 is provided, rearwardly of such projections, with a pair of projections 8^d, each being carried by a flange 8^b and having its rear or inner face preferably constituting an extension of the corresponding face of the web 8^a. The front or outer face of each projection 8^d is inwardly or rearwardly beveled from the flange 8^b, as indicated at 8^e. The purpose of this construction will be explained in connection with the two rear clamping members, which will now be described.

Each of the rear clamping members consists generally of a body 9 having depending flanges 9^a at each side thereof. At their inner or rear edges, each of these members is provided with a notched or channeled seat 9^b, the seats jointly receiving the upper and the lower edge of the auxiliary bar or plate 3. At its outer or front end, each member 9 is provided with a flange 9^c which is adapted to be inserted between the rear or inner face of a bar or plate 1 and a projection 8^d. The portion of each flange 9^c which engages the beveled face of its projection 8^d is also preferably beveled, as indicated at 9^e.

Each of the members 9 is provided with an opening 9^f in the central portion thereof, with a seat 9^g surrounding such opening.

A bolt 10 extends through these openings having its head 10^a adapted to engage one of the seats 9^c and a washer 10^b adapted to engage the other seat when the nut 10^c is set up.

With the parts arranged and connected as described, it will be evident that, by setting up the nut 10^c, the clamping members 9 will be drawn together, causing the plate 3 to be firmly secured in the seats 9^b, while the plate 1 will be wedged against the flanges or projections 8^c through the action of the wedged surfaces 9^d and 8^d.

The front member 8 is provided with a pair of tapped openings 8^d for the application of a name plate thereto within the channelled seat provided by such member.

The construction disclosed herein is simple and economical of production, but is particularly efficient in securing a firm connection between the front and the rear plates or bars of the bumper; it can be readily and conveniently applied to the said bars or plates; and it will prevent the rattling of the various parts when in use.

Having thus described my invention, what I claim is:

1. A clamping device for securing together the vertically spaced impact bars and the intermediate and laterally spaced auxiliary bar of a bumper, said device comprising a member having upper and lower seating portions, for the adjacent edges of the main bars, a pair of members each having a portion adapted to engage an impact bar and form a seat therefor with the cooperating seating portion of the first member, each of the last two members also having a seat for an edge of the intermediate auxiliary bar, and means intermediate of the ends of the last two members for adjusting the same toward each other.

2. A clamping device for securing together the vertically spaced impact bars and the intermediate and laterally spaced auxiliary bar of a bumper, said device comprising a member having seating portions adapted to engage the adjacent lower and upper edges of the said impact bars and the front or outer lateral surfaces of said bars, respectively, a pair of members each having a portion adapted to engage the inner or rear lateral face of an impact bar opposite the face-engaging portions of the first member, respectively, and each also having a seat for an edge of the intermediate auxiliary bar, and means for adjusting the said pair of members toward each other.

3. A clamping device for securing together the vertically spaced impact bars and the intermediate and laterally spaced auxiliary bar of a bumper, said device comprising a member having seating portions adapted to engage the adjacent lower and upper edges of the said impact bars and the

front or outer lateral surfaces of said plates, respectively, a pair of members each having a portion adapted to engage the inner or rear lateral face of an impact bar opposite the face-engaging portions of the first member, respectively, and each also having a seat for an edge of the intermediate auxiliary bar or plate, means for adjusting the pair of members toward each other, and means cooperating with the bar-engaging portions of the two last-mentioned members for forcing the same toward and into engagement with their respective impact bars through the operation of said adjusting means.

4. A clamping device for securing together the vertically spaced impact bars and the intermediate and laterally spaced auxiliary bar of a bumper, said device comprising a member having a central base and a flange projecting outwardly or forwardly from the top and a flange projecting in like manner from the bottom of such base and a substantially vertical projection extending from each such flange, each projection and the outer portion of its flange constituting respectively a bearing face for the outer face of an impact bar and a seat for the adjacent edge of such bar, the said member having an upper and a lower projection each having a beveled or tapered surface presented toward the bar-engaging surface thereof, a pair of clamping members each having a portion adapted to engage the inner or rear face of an impact bar and a surface adapted to engage the beveled or tapered surface on one of such projections and each adapted to engage an edge of the auxiliary bar or plate, and means for drawing the clamping members toward each other.

5. A clamping device for securing together the vertically spaced impact bars and the intermediate and laterally spaced auxiliary bar of a bumper, said device comprising a member having a central base and an inner and an outer projection at the top and at the bottom thereof respectively, each outer projection being adapted to engage the outer face of an impact bar adjacent thereto and each inner projection having a beveled or tapered surface presented toward its outer projection, a pair of clamping members each having a portion adapted to engage the inner or rear face of an impact bar and a surface adapted to engage the beveled or tapered surface of an inner projection, each clamping member also being a seat for an edge of the auxiliary bar, and means for drawing the clamping members toward each other.

6. A clamping device for securing together the vertically spaced impact bars and the intermediate and laterally spaced auxiliary bar of a bumper, said device comprising

- ing a member provided with a surface adapted to engage the adjacent portions of the outer or front faces of the impact bars, respectively, and having tapered surfaces 5 opposed to the first mentioned surfaces, a pair of members each having a seat for an edge of the auxiliary bar and each having a portion adapted to be interposed between the rear or inner face of an impact bar and 10 one of such tapered surfaces, and means for drawing the last two members toward each other.
7. A clamping device for securing together the vertically spaced impact bars and 15 the intermediate and laterally spaced auxiliary bar of a bumper, said device comprising a seating member having a pair of bearing surfaces adapted respectively to engage the lower, outer face of the upper main bar and the upper outer face of the lower impact bar, respectively, a pair of clamping members each having a seat for an edge of the auxiliary bar, means for adjusting 20 the last two members toward each other, and means operative by such movement of 25 the last two members toward each other for forcing the upper and lower impact bars
- against the cooperating bearing surfaces of the seating member.
8. A clamping device for securing together the vertically spaced impact bars and the intermediate and laterally spaced auxiliary bar of a bumper, said device comprising a seating member having a pair of bearing surfaces adapted respectively to engage 30 the lower, outer surface of the upper impact bar and the upper, outer face of the lower impact bar, a pair of clamping members each having a seat for an edge of the auxiliary bar, means for adjusting the last two 35 members toward each other, each of the last two members having a surface opposed to a bearing surface on the first mentioned member, and tapered surfaces carried by the first member and adapted to be engaged by such 40 portions of the clamping members, whereby the adjustment of the said clamping members toward each other will firmly clamp the said impact bars between such opposed 45 bearing portions on the seating member and 50 on the clamping members.

In testimony whereof, I hereunto affix my signature.

WAYNE E. DUNSTON.
